Primary Examiner — W. A. Teddy Falloway*Assistant Examiner* — Amanda Kay Birdwell(74) *Attorney, Agent, or Firm* — Bycer & Marion, PLC;
Matthew L. Bycer(57) **CLAIM**

The ornamental design for a container with lid as shown and described.

DESCRIPTION

FIG. 1 illustrates a top perspective view of the container with lid, with lid removed at side and upside down demonstrating the interior;

FIG. 2 illustrates a side view thereof;

FIG. 3 illustrates a top plan view thereof;

FIG. 4 illustrates a bottom plan view thereof;

FIG. 5 illustrates a top perspective view of the exterior of the container with lid applied; and,

FIG. 6 illustrates an exploded view thereof.

The broken lines shown in the drawings represent portions of the container with lid that form no part of the claimed design.

1 Claim, 6 Drawing Sheets(56)
